UNITED STATES PATENT OFFICE

2,329,030

HACKSAW BLADE HOLDER

Rudolph Baronick, Langeloth, Pa.

Application March 20, 1942, Serial No. 435,553

1 Claim. (Cl. 145—34)

The present invention relates to new and useful improvements in hack-saws, and has for its primary object to provide a pair of telescoping frame sections adapted for securing the blade in position thereon and embodying means for locking the sections of the frame with the blade under tension.

A further object of the invention is to provide a blade holder by means of which the blade may be attached in a position either vertically or horizontally with respect to the frame.

A still further object is to provide a device of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a side elevational view.

Figure 2 is a top plan view.

Figure 3 is a fragmentary side elevational view of the front end of the frame with parts shown in section.

Figure 4 is a fragmentary longitudinal sectional view of the rear or handle end of the frame.

Figure 5 is a sectional view taken substantially on a line 5—5 of Figure 1.

Figure 6 is a similar view taken substantially on a line 6—6 of Figure 1, and

Figure 7 is a bottom plan of the link connecting the clamping lever to the clamp for securing the sections of the frame in a locked position.

Referring now to the drawings in detail, wherein for the purpose of illustration I have disclosed a preferred embodiment of the invention, the numeral 5 designates the hack-saw frame generally which includes an outer section 6 and an inner section 7, the outer section being of substantially L-shaped construction and the inner section including a tubular member 8 to the rear end of which is secured the handle 9. Extending downwardly from the tubular section 8, adjacent the handle, is a supporting bracket 10 having a tubular guide 11 at its lower end within which is slidably mounted a connector 12 for the rear end of the blade 13.

The guide 11 is of square shape in cross-section and is provided on its front portion, at one side thereof, with a hook member 14 adapted

for engaging in the opening of the blade and a similar hook member 15 projecting downwardly from the underside of the connector, the hook members 14 and 15 being spaced longitudinally on the connector, as shown to advantage in Figure 1 of the drawings.

The rear end of the connector projects rearwardly from the guide 11 and is provided with a coil spring 16 held under compression against the guide by means of a washer 17 secured to the end of the connector by a screw 18, the spring urging the connector rearwardly.

To the lower end of the front section 6 is secured a similar guide member 19 having a connector 20 secured therein by means of a pin 21. The connector 20 is also formed on its side and bottom edges with longitudinally spaced hook members 22 and 23, respectively, for engagement with the front end of the blade 13.

Accordingly, it will be apparent that the blade may be supported in a vertical position with respect to the frame by attaching the blade to the hooks 14 and 22, or the blade may be supported in a horizontal position by attaching the blade 25 to the hooks 15 and 23.

Positioned in the tubular frame member 8 is a coil spring 24 engaging the rear end of the frame member 6 for projecting the same forwardly.

To the lower edge of the rear end of the frame member 6 is formed a notch 25 engageable by a pivoted dog 26 pivotally mounted on a pin 27 extending transversely between a pair of spaced ears 28 formed on the split edge on the underside of the tubular member 8 at its front end.

A wire spring member 29 is coiled about the pivot pin 27 with one edge engaging the dog 26 to yieldably urge the same upwardly for engagement in the notch 25 and the other end of the wire spring engages the edge of the ears 28. Accordingly the dog prevents the complete outward separating movement of the sections of the frame 6 with respect to the tubular section 8.

Also pivoted on the pin 27 is a lever 30 of channel shape in cross-section and adapted to straddle the upper edge of the tubular member 8 for movement into a position longitudinally of the frame, as shown to advantage in Figure 1 of the drawings. The lever is pivoted rearwardly of its front end and is provided with a pin 31 positioned forwardly of the pin 27 and a link 32 has its rear end pivoted on the pin 31. To the front end of the link 32 is pivotally attached a cam link 33 having its cam end 34 extending up-

55

wardly for engagement with the lower edge of the telescoping part of the frame member 6.

A U-shaped clamp 35 straddles the frame member 6 and is pivotally connected at its lower end to the cam link 33, as shown to advantage in Figure 3 of the drawings.

A leaf spring 36 has one end attached to the underside of the link 32 adjacent its front end and the spring is provided at its free end with a bifurcation 37, which extends upwardly for receiving the frame member 6, the upper end of the spring bearing against the clamping member 35 for urging the same in a direction toward the front end of the tubular member 8.

In the operation of the device, by raising the lever 30 upwardly, the rear end of the link 32 is moved downwardly and rearwardly, thereby swinging the cam end 34 of the cam link 33 away from engagement with the frame section 6 and thus releasing the clamp 35. The spring 24 then functions to project the frame section 6 forwardly to spread the frame sections apart whereby to exert tension on the blade 13. When the lever 30 is lowered the rear end of the link 32 is raised upwardly and moved forwardly, thereby moving the cam end 34 of the cam link 33 into engagement with the frame section 6 and causing a locking engagement of the clamp 35 therewith. The spring member 16 on the connector 12 also

urges said connector rearwardly to apply tension to the blade 13 in a manner as will be apparent.

It is believed the details of construction, manner of operation and advantages of the device will be apparent from the foregoing without further detailed explanation.

Having thus described the invention what I claim is:

A hack saw frame comprising a pair of telescoping frame members including spaced parallel parts, means for detachably connecting the ends of a saw blade to said parts, means for clamping the frame members to each other to secure the same in adjusted position, said last-named means comprising a lever pivoted to one frame member, a clamp loosely carried by the other frame member, links pivotally connecting the lever and the clamp and including a connecting link and a cam link having a cam at one end, said cam link being pivoted adjacent its cam end to the clamp and pivoted at its other end to the connecting link leading to the lever and adapted for movement of said cam end into binding engagement against the said other frame member upon a predetermined movement of the lever, and a leaf spring carried by said connecting link and engaging the clamp to maintain the latter against canting during movement thereof on the frame.

RUDOLPH BARONICK.
